UNITED STATES PATENT OFFICE.

EDWARD FIXTER, OF SHARON, PENNSYLVANIA, ASSIGNOR OF ONE-HALF TO THOMAS J. HORNE, OF SHARPSVILLE, PENNSYLVANIA.

RAIL-JOINT.

No. 914,128.

Specification of Letters Patent. Patented March 2, 1869.

Application filed December 10, 1868. Serial No. 466,827.

To all whom it may concern:

Be it known that I, EDWARD FIXTER, a subject of the King of Great Britain, residing at Sharon, in the county of Mercer and State of Pennsylvania, have invented certain new and useful Improvements in Rail-Joints, of which the following is a specification, reference being had therein to the accompanying drawing.

10 This invention relates to rail joints, and the object of my invention is the provision of positive and reliable means for connecting the confronting ends of two rails, to provide practically continuous tread for rolling stock, 15 to prevent the rails from becoming accidentally displaced, and to obviate the necessity of using nuts and bolts as a connecting medium for the confronting ends of rails.

I attain the above objects by a connecting link that is easily and quickly installed by unskilled labor and applicable as a rail connecting medium either upon straight tracks, curves or bridges. In either instance, the connecting link insures a positive connection 25 between rails, for the circuits of railway signals, and increases the life of the rails, at the joints thereof.

The detail construction entering into my invention will be hereinafter described and 30 then distinctly pointed out in the appended claim.

In the drawings, Figure 1 is a perspective view of the connecting link of two rails constructed in accordance with my invention, 35 Fig. 2 is a similar view of the confronting ends of two rails constructed to accommodate the connecting link, Fig. 3 is a cross sectional view of a rail joint, Fig. 4 is an elevation of the same, partly broken away and partly 40 in section, Fig. 5 is a perspective view of the connecting link employed for joining a previously installed rail with a newly laid rail, Fig. 6 is a similar view showing the confronting ends of a previously installed 45 and newly laid rail, Fig. 7 is a cross sectional view of the connecting link in connection with an installed rail, and Fig. 8 is a side elevation of the same partly broken away and partly in section.

50 In the accompanying drawings, I have illustrated the confronting ends of two rails, said rails comprising base flanges 1, webs 2 and heads 3, said heads being cut away at the ends of the rails, as at 4.

55 The coupling link used for connecting the

rails comprises splice bars 5 having a connecting head or tread 6 and an intermediate connecting web 7. The intermediate connecting web 7 is placed between the ends of the webs 2 of the rails, while the connecting 60 head or tread 6 is arranged between the confronting ends of the heads 3 of the rails. The splice bars 5 embrace the web 2 and the base flanges 1, and the connecting link in its entirety provides a continuous tread for the 65 rolling stock adapted to pass over the rails. To secure the connecting link in position upon ties 8 spikes 9 are used, said spikes extending downwardly through notches 10 provided therefor in the longitudinal edges 70 of the splice bars 5.

In order that an ordinary rail can be connected by the link to a rail having the head thereof cut away, connecting links are provided with the heads or treads 6 thereof cut 75 away, as indicated at 11 in Fig. 5 of the drawings, and clearly shown in Fig. 8 of the drawings, where it will be observed that the splice bars 5 embrace the web 2 of an ordinary rail.

80 It is thought that the manner of assembling my rail joint will be fully understood without further description, and while in the drawings there is illustrated the preferred form of construction embodying the invention, it is obvious that the elements therein may be varied or changed, without departing from the spirit of the invention.

Having now described my invention, what I claim as new, is:

90 In a rail joint, the combination with rails having the heads thereof cut away at the ends of said rails, of a connecting link for the confronting ends of said rails, said connecting link comprising splice bars having a connecting head or tread and an intermediate web adapted to fit between the confronting ends of said rails, with the splice bars thereof embracing said rails, and the head or tread of said link forming a continuous tread between the cut away heads of said rails, and means for securing said connecting link in position, relative to the confronting ends of rails, substantially as described.

95 In testimony whereof I affix my signature 105 in the presence of two witnesses.

EDWARD FIXTER.

Witnesses:

MAX H. SHOLOVITZ,
C. V. BROOKS.
